UNITED STATES PATENT OFFICE.

FERDINAND S. OPPENHEIM, OF NEW YORK, N. Y.

CONTAINER.

Application filed August 1, 1925. Serial No. 47,469.

This invention relates to packing and shipping boxes and cases. More particularly, it is directed to corrugated paper board containers or cartons of improved construction for packing and shipping delicate apparatus such as radio sets, meters, typewriters, and the like.

An object of the invention is to provide an improved container or carton of the character described having a braced inner wall structure for reinforcing the outer walls to effectively protect and cushion the enclosed contents from sudden blows and contacts so as to prevent injury and damage due to careless and rough handling during transportation and which includes one or more cushioning members of improved construction having means associated therewith for bracing the adjacent side wall of the outer container casing.

Another object of the invention is to provide an improved container or carton of the character described which is simple in construction, cheap to manufacture, and efficient and practical to a high degree for the purposes described.

Other objects of this invention will in part be obvious and in part hereinafter pointed out.

The invention accordingly consists in the features of construction, combinations of elements and arrangement of parts which will be exemplified in the construction hereinafter described and of which the scope of application will be indicated in the following claims.

In the accompanying drawing, in which is shown one of the various possible illustrative embodiments of this invention,

Fig. 1 is a perspective view showing a packing and shipping box embodying the invention, parts of the box being broken away to show the interior;

Fig. 2 is a cross-sectional view taken on line 2-2 in Fig. 1 showing the box closed and sealed with the contents (shown at a) packed therein;

Fig. 3 is a perspective view of a side cushioning member or partition liner;

Fig. 4 is a plan view of a blank from which the top cushioning member shown in Figs. 1, 2 and 5 is formed; and Fig. 5 is a perspective view of the improved top cushioning member.

Referring in detail to the drawing, 10 denotes an outer casing or shell of a packing and shipping box embodying the invention which may have any desired shape or design

and may be made of fibre board, card board, or the like material, but is preferably constructed of corrugated paper board, the cellular structure of which has been found to add greatly to the cushioning effect for the purposes described.

As seen in Fig. 1, the outer casing 10 is of collapsible construction and comprises elongated side walls 11, end walls 12, and cover flaps 13, 14, 15 and 16, all preferably formed from a single sheet of material, cut, creased, and folded to form the rectangular shaped shell 10, the cover flaps being adapted to fold inwardly to form the top and bottom walls 70 for closing the casing. When the flaps are folded into their closed position, they may be held in place by any suitable means as for example a strip of adhesive tape 17.

Partition liners or cushioning members 18 are provided which are arranged against the side walls, end walls and the bottom of the casing 10. Each of these members 18 may be of any suitable and substantially identical construction and as seen most clearly from Fig. 3 is preferably formed of a single sheet of corrugated paper board, cut, creased and folded to form a rectangular shaped body portion 19, end walls 20, and side walls 21, said end walls 20 having flap extensions 22 which are bent to extend within and adjacent the side walls 21 and held in position by suitable fastening means. The flap extensions 22 or other fastenings for the side and end walls to retain them in their relative positions may be omitted if desired, since it is apparent that when the members 18 are assembled within the casing 10, the structure is self-retaining. (See Fig. 2.)

It will be understood that the shipping box is of suitable dimensions to enable packing the article or articles therein so as to substantially fill the space marked A in Fig. 2, and that the partition liners 18 are of proper design to completely cover the interior sides and the bottom of the casing.

As seen from Figs. 1 and 5, the top cushioning member 23 is preferably constructed of a single sheet of corrugated paper board, cut to the blank shape 23^a shown in Fig. 4 and provided with crease lines 23^b so that the blank 23^a may be formed into a folded structure shown in Fig. 5. The member 23 is seen to have a central rectangular receptacle portion 24 in one side thereof, the upstanding side walls 25 and 26 of which serve to cushion and space the contents from the top of the

casing. Each of said walls 25 and 26 may have outwardly extending edge flaps 25^a and 26^a respectively which are adapted to support the cushioning member 23 on the inner wall structure and also to reinforce the corner bracing of the box as shown in Figs. 1 and 2. The ends of each flap 26^a may be provided with inwardly disposed flap extensions 26^b for supporting said flaps. (See Figs. 1 and 5.)

To provide a braced inner wall structure for the contents or article to be packed when such is relatively heavy or if the shipping box is liable to be subjected to unusual rough handling during transportation, each partition liner or member 18 and 23 has fitted therein a bracing member 18^a which may be constructed similarly to said liner 18 and proportioned to just fill the body portion 19 of liner 18 and the recessed portion 24 of member 23. Thus said bracing member 18^a forms a secondary abutting reinforcing wall for the casing 10 as shown in Figs. 1 and 2.

In the practice of the invention, the side and end partition liners 18 with the bracing members 18^a fitted therein are first placed in position in casing 10 and are held in their respective places as shown in Figs. 1 and 2 by cushioning member 23 fitted with a member 18^a. Having arranged these braced liners in position with their body portion spaced inwardly from the various side walls of the casing, the article to be packed is then lowered into place, the side wall of the article abutting 35 against the walls of the liners 18 and being spaced thereby a substantial distance from the walls of the casing 10.

With these parts in position, a cushioning member 23 fitted with a bracing member 18^a in its receptacle portion 24 is inserted in the top opening of the casing, the member 23 being dimensioned to the proper height to fill the space between the top of the contents and the top of the casing as shown in Figs. 1 and 2. The cover flaps are then folded into position and the casing sealed in any suitable manner as by means of a strip of adhesive tape 17.

In utilizing the structural form of top cushioning member 23 described, the side and end liners 18 are preferably arranged to extend substantially to the top of the casing and the flaps 25^a and 26^a of said member 23 may be supported on the liners 18, said flaps being thus arranged to reinforce the corners and corner edge portions of the casing 10 which the bracing member 18^a serves to reinforce the adjacent wall of the casing 10.

It will thus be seen that there is provided a device in which the several objects of this invention are achieved and which is well adapted to meet the conditions of practical use.

As various possible embodiments might be made of the above invention, and as various changes might be made in the embodiment above set forth, it is to be understood that all

matter herein set forth or shown in the accompanying drawing is to be interpreted as illustrative and not in a limiting sense.

Having thus described my invention, I claim as new and desire to secure by Letters Patent:—

1. A packing and shipping box comprising an outer casing having a pair of similarly constructed partition liners nested and arranged in the casing for each of the walls thereof, said liners forming a hollow supporting structure in the casing adapted to protect and cushion the enclosed contents against damage during transportation. 75

2. A packing and shipping box comprising an outer casing having a pair of similarly constructed partition liners nested and arranged in the casing for each of the walls thereof, said liners forming a hollow supporting structure in the casing adapted to protect and cushion the enclosed contents against damage during transportation, one of said pair of liners abutting an adjacent wall of the casing to form a reinforcement therefor. 80

3. A packing and shipping box comprising an outer casing having separate removable partition liners arranged therein for each of the side walls of said casing, a bracing member demountably fitted into each of said liners to form a hollow structure, said member abutting a wall of the casing to form a reinforcement therefor, said liners and members being substantially similar in shape and construction. 100

4. A packing and shipping box comprising an outer casing having separate removable partition liners arranged therein for each of the side walls of said casing, said liners having a recessed body portion and a bracing member of substantially the same shape and construction as said liner demountably nested in each of said liners to form a hollow double wall cushioning structure for each side wall of said casing. 105

5. In a packing and shipping box of the character described having an outer casing, an inner wall cushioning structure for said casing comprising non-intersecting removable sections each consisting of two similarly shaped parts fitted together to form a hollow structure having parallel spaced walls, one of said section walls abutting the entire adjacent wall of said casing. 115

6. In a packing and shipping box of the character described having an outer casing, a plurality of removable spacing partitions arranged to abut one another to form the inner walls of the box, at least one of said partitions having a central receptacle portion and flaps extending outwardly from the side walls of said portion, and a member similar in shape and construction to said receptacle portion fitted into the latter to form a hollow wall structure abutting the adjacent side of 120 125 130

the casing and extending to brace the entire said side when the partition is in place.

7. In a packing and shipping box, a cushioning liner made of a single piece of corrugated paper board cut into a blank, creased, and folded to have a central receptacle portion adapted to receive a member for bracing a wall of the casing, edge flaps extend-

ing from the walls of said portion and inwardly disposed tabs formed on the ends of said flaps, said tabs being positioned in superimposed abutting relation with respect to the ends of the adjacent edge flaps. 10

In testimony whereof I affix my signature.

FERDINAND S. OPPENHEIM.
